US0D1020794S

(12) **United States Design Patent** (10) **Patent No.:** **US D1,020,794 S**
(45) **Date of Patent:** **** Apr. 2, 2024**

(54) **MEDICATION DELIVERY DEVICE WITH ICONS**

(71) Applicant: **Insulet Corporation**, Acton, MA (US)

(72) Inventors: **Bryan Mazlish**, Palo Alto, CA (US); **Sabine Kabel-Eckes**, Mountain View, CA (US); **Jeff Boissier**, San Jose, CA (US); **Bethany Leigh Salmon**, San Jose, CA (US)

(73) Assignee: **BIGFOOT BIOMEDICAL, INC.**, Milpitas, CA (US)

(**) Term: **15 Years**

(21) Appl. No.: **29/788,431**

(22) Filed: **May 25, 2021**

Related U.S. Application Data

(62) Division of application No. 29/642,766, filed on Apr. 2, 2018, now Pat. No. Des. 928,199.

(57) **CLAIM**

The ornamental design for a medication delivery device with icons, as shown and described.

DESCRIPTION

FIG. 1 is a front view of a medication delivery device with icons showing an embodiment of the design.

FIG. 2 is a front view showing an embodiment of the design.

FIG. 3 is a front view showing an embodiment of the design; and,

FIG. 4 is a front view showing an embodiment of the design. The broken lines illustrate portions of the medication delivery device with icons that form no part of the claimed design.
